UNITED STATES PATENT OFFICE.

GEORGE WASHINGTON SHOEMAKER, OF DALTON, PENNSYLVANIA.

RING-SPINNING MACHINE.

SPECIFICATION forming part of Letters Patent No. 357,864, dated February 15, 1887.

Application filed April 3, 1886. Serial No. 197,692. (No model.)

To all whom it may concern:

Be it known that I, GEORGE WASHINGTON SHOEMAKER, a citizen of the United States, residing at Dalton, in the county of Lackawanna 5 and State of Pennsylvania, have invented certain new and useful Improvements in Ring-Spinning Machines; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15. Figure 1 is an elevation of one end of my improved ring-spinning machine, showing the drawing-rolls near the terminus of their down-stroke. Fig. 2 is a front elevation of the machine, parts of one end of the same being broken 20 away. Fig. 3 is a section taken horizontally through Figs. 1 and 2 in the plane indicated by dotted lines $x-x$ thereon, showing parts of some of the driving-bands removed. Fig. 4 is a detail of the fast cam B^3 and parts connected 25 therewith. Fig. 5 is an enlarged perspective view of part of the main frame, its drawing-rolls, endless race-belt, and pitman-rod for the lower drawing-roll carriage.

30. My invention relates to certain novel improvements which are applicable to continuous drawing and ring-spinning machines for spinning wool, cotton, and other fibrous materials, which will be hereinafter more fully described and pointed out.

35. Referring by letter to the accompanying drawings, A designates the main frame, and A' the main driving-shaft suitably journaled thereon.

B designates a shaft driven from the main 40 shaft A' by means of a pinion spur-wheel, a, keyed on the latter, engaging with a master spur-wheel, b, on shaft B, as clearly shown in Figs. 1 and 2.

C is a shaft which receives rotation from the 45 shaft B by the wheel b, engaging with a pinion, c, keyed on shaft C.

D is a spur-wheel which receives rotation from the large spur-wheel C on the shaft C through the medium of a spur-wheel, e, keyed 50 on the end of a shaft, e', of a drum, X². This spur-wheel D transmits rotation directly to the feed-rolls E E by engaging with twin

spurred pinions e³ e³, (shown clearly in Fig. 1,) and F are movable rolls which rest on the feed-rolls E E.

55

An endless belt, B², runs from a band-wheel, a', keyed on the main shaft A', under a band-wheel, G, keyed on a shaft, G', thence over an idler-pulley, J, and around a band-wheel, K, on a worm-shaft, K'. The shaft G' transmits to rotation to a shaft, H, at right angles to it, by means of a beveled pinion, H², keyed on said shaft G', which pinion engages with a large bevel spur-wheel, H⁴, keyed on shaft H. On this shaft H is a bevel-pinion, 2, which engages 65 with a similar pinion, 3, keyed on the lower end of a shaft, I, which latter in turn transmits motion to a shaft, B⁴, bearing a cam, B³, by means of the beveled pinions H³ and H⁴.

The cam B' (shown clearly in Figs. 2 and 3) 70 receives its movements from the shaft K' through the medium of the worm A⁴ and worm-wheel L, and said band-wheel K receives rotation from the main driving-shaft by means of the same belt, B², which rotates the shaft G', 75 as above described.

M' designates a rectilinear reciprocating carriage, which is guided between points f f on an inclined way, N, and which bears the drawing-rolls R' R', on top of which are other rolls, S. 80 The journals of the drawing-rolls R' R' bear race-pulleys R R, which impinge upwardly against the upper half of an endless race-belt, O, hereinafter referred to. The drawing-roll carriage M' receives its traversing movements 85 from the master spur-wheel b by means of a pitman-rod, M, connected to the wheel by a wrist-pin, M². (Shown in Fig. 1.)

The endless race-belt O runs from the pulley O' on the shaft C to a pulley, P, which 90 turns freely on a stud fixed to the side of the main frame A. The frame M' receives an alternate forward and receding motion, and simultaneously therewith these rolls R R receive rotary motion by reason of the frictional contact of their race-pulleys with the under side of the upper half of the belt O. The spindles P' receive rapid rotation for effecting the spinning of the rovings from a horizontal cylinder, T, journaled in the main frame A and 100 receiving rotation from a pulley, a', on the main shaft, acting through the medium of an endless belt, V, and a pulley, a², on the shaft of the said cylinder.

95

100

X is a spool, from which is unwound the rovings by means of a drum, X², on which the same impinges, which drum is on the shaft e' of the intermediate gear-wheel, e, that derives its rotation from the spur-wheel a on the main shaft A', acting through the medium of the master spur-wheel b, pinion c, and large spur-wheel C² above described. The journal of each end of spool X may bear upon a bracket, X', as shown in Figs. 1 and 2.

A² is the horizontal vertically-movable ring-rail supporting the rings B³ and their travelers C', and A³ is the rail on which the spindles P are stepped. The cam B' gives the ring-rail a slow steady upward motion until it reaches the terminus of its upward stroke, when this rail speedily descends to a point--say one inch--below the bobbin D². The motion of this cam is communicated to the ring-rail A² by means of the curved rider E', projecting from one of the levers F', (the free end of which rider bears on the convex surface of the cam, as indicated in Fig. 2,) levers F² F², and vibrating arms G⁷ G⁷, which latter are connected by pivots and slots to vertical reciprocating staffs G² G², that pass freely through the step-rail A³ and are rigidly secured to the ring-rail A². The ring-rail has a subsidiary motion given to it by the cam B³, the shaft B⁴ of which has its bearing on the upper free end of the left-hand vibrating lever F² and vibrates concentrically with the axis of the shaft H. This cam B³ acts on the hook end of a rider, B⁷, adjustably secured to a horizontal rod, B⁸, to which the right-hand lever or levers F² are suitably pivoted. The forward end of the rider B⁷ is provided with a longitudinal aperture for the reception of the horizontal rod B⁸, and this apertured portion is provided transversely with one or more threaded perforations for the passage of screws or bolts which adjustably secure the said rod to the rider. This mechanism B³ is substantially similar in construction to the mechanism B' so far as the cam and rider are concerned; but the cam B³ is adapted to make, say, from fifty to seventy-five revolutions while cam B' makes but one revolution, and cam B³ is driven by bevel-gears H³ H⁴, whereas cam B' is driven by worm A⁴ and gear K, thereby in a simple manner obtaining the proper rates of speed of the said two cams. In practice the cam B³ has a throw of from one to one and a half inch. The bevel-gear H³ H⁴ and shaft I are applied on the left-hand lever F² and vibrate with it the beveled gears 2 3, maintaining a perfect mesh at all points of the vibration with the bevel-gear 2 3. The cam B' gives the build and outline to a complete cop, while the cam B³ gives the rapid motion which forms the nose of the cops.

The travelers C' deliver the yarn on the bobbin as fast as it is paid out from the drawing-rolls, and the drawing-rolls R' R' deliver the yarn completely drawn and partially twisted over the notched guide-rail W to the spindles P, which give the yarn its complement of twist. By reference to Figs. 1 and 5, it will be ob-

served that the race-belt O moves in the direction of the arrows. This belt has a speed equal to the desired feed of the rovings to the spindles, 70 and the action of this belt on the latter is as follows: As above described, the belt O passes over and turns the race-pulleys R R on said roller-journals. These race-pulleys being of the same diameter as their rolls, it follows that the 75 same rotary speed is given to the rolls that is given to the race-pulleys which drive them. The driving or pitman rod M gives this drawing mechanism an alternate reciprocating motion, which directly affects the speed of said 80 rolls, but not the speed of the race-belt O. The speed of the drawing-rolls is affected as follows: First, when these rolls are receding from the spindles, the speed increases over the normal movement of the race-belt to cover the distance passed over, (from points f to f';) and, second, in the downward or forward movement toward the spindles the drawing mechanism moves much faster than the race-belt and causes the rolls R' R' to receive rotary motion 90 in a direction opposite to that which they have while receding.

The operation is as follows: The rovings pass out from the feed-rolls E E to the drawing-rolls R' R', which must have a greater 95 speed than that of the rolls E E, and are thereby caused to draw the rovings to any attenuated degree desired; but it is necessary that a certain per centum of twist be present at the place of drawing, which place is between the feed-rolls and the drawing-rolls, and the bodily-reciprocating movements of these latter rolls allow the twist necessary for the drawing of even yarn to pass up to the said place of drawing. As the drawing mechanism moves forward, the drawing-rolls run downward upon the yarn between the guide-rail W and the feed-rolls E E, while the spindles are constantly giving the yarn its finishing twist. After this twist is passed over by the drawing-rolls in their forward motion these rolls recede again, during which movement the twist is allowed, as it comes from the spindles, to follow the rolls up until they move downward again to run over the twist, as before described. Different degrees of twist are given to the yarn by increasing or diminishing the velocity of the cylinder T, which rotates the spindles relatively to the speed of the drawing-rolls, and the amount of twist allowed at 100 the place of draft is regulated by the throws of the drawing-rolls per minute. 110

Having described this invention, what I claim is—

1. In a ring-spinning machine, the combination of bodily reciprocating and rotating drawing-rolls with feed-rolls, an endless race-belt, a pitman-driver, and means, as described, for operating the said feed-rolls, race-belt, and pitman-driver, substantially as specified. 125

2. In a ring-spinning machine, the combination, with the main frame having an inclined guideway, of a reciprocating carriage bearing drawing-rolls, means for giving a posi- 130

tive reciprocating motion to said carriage, and an endless belt moving continuously in one direction for rotating said rolls, and feed-rolls located between the drawing-rolls and roving-
5 spool, substantially as specified.

3. The combination, in a ring-spinning machine, of bodily reciprocating and rotating drawing-rolls, mechanism, substantially as described, for giving said movements to the rolls, feed-rolls in rear thereof, and a guide-rail and spindles in front thereof, substantially as specified.

4. The combination, with the main driving-shaft, of the master-wheel *b* and its driving-
15 pinion, bodily-reciprocating drawing-rolls, the pitman connecting said master-wheel directly to the carriage bearing said rolls, the carriage, a train of gearing, an endless race-belt receiving movement continuously in one direction
20 from said main shaft through the medium of the train of gearing, and race-pulleys on the journals of said rolls impinging against and rotated by said belt, substantially as specified.

5. In a continuous ring-spinning machine, the combination of feed-rolls, the carriage bearing the drawing-rolls, means, as described, for reciprocating the carriage, the spindles, the mechanism for actuating the spindles, the race-
25

pulleys and driving-belt for the drawing-rolls, as described, a vertically-movable ring-rail, 30 fast and slow cams and their riders, and devices intermediate of the riders and ring-rail, substantially as specified.

6. The combination, with the vertically-movable ring-rail and its supporting-staffs and the vibrating arms, of vibrating levers *F*², one of which bears a fast cam, *B*³, actuating mechanism for said cam, a rider, *E*', the slow cam *B*', its worm-wheel and worm, the rider *B*', the rod *B*⁸, the shaft *K*', the driving-pulleys, the 40 driving-belt, and the main shaft *A*', substantially as specified.

7. In combination with the main frame of a ring-spinning machine, drawing-rolls which receive a bodily rectilinear reciprocating 45 movement, means, as described, for reciprocating the carriage and rolls, and an endless belt applied to rotate said rolls during said movement, substantially as specified.

In testimony whereof I affix my signature in 50 presence of two witnesses.
